UNITED STATES PATENT OFFICE.

JOHN COWAN, OF EDINBURGH, SCOTLAND.

WATER-TUBE BOILER.

SPECIFICATION forming part of Letters Patent No. 729,738, dated June 2, 1903.

Application filed October 3, 1901. Serial No. 77,456. (No model.)

To all whom it may concern:

Be it known that I, JOHN COWAN, managing director of The Stirling Boiler Company, Limited, a subject of the King of Great Britain and Ireland, residing at 2 St. Andrew's Square, Edinburgh, Scotland, have invented certain new and useful Improvements in Water-Tube Boilers, (for which I have made application for patent in Great Britain, No. 9,924, dated 10 May 13, 1901,) of which the following is a specification.

My invention relates to water-tube boilers, especially the "Stirling" type of boiler.

The unsteady motion to which marine boilers are subjected tends to produce agitation of the water in the drums and consequent wetness of the steam and priming, and even in land-boilers of approved construction these evils may occur when water having a frothy 20 tendency is used.

The object of my invention is to increase the dryness of steam generated under ordinary conditions and to insure the production of dry steam under such adverse conditions 25 as those above referred to.

My invention consists also in increasing the effective distance between the water-level in the boiler and the steam-outlet pipe by providing a box partition or baffle within a drum 30 from which steam is drawn and in arranging the steam-outlet to draw from this pocket only, the pocket being arranged to be fed with steam only from or through one or more of the other drums, whereby the steam is thoroughly dried before it leaves the steam-outlet. 35

My invention also consists in increasing the effective distance between the water-level and the steam-pipes which connect the drums by means of suitable baffles, as hereinafter de- 40 scribed.

Referring now to the accompanying drawings, Figure 1 is a sectional side elevation of a Stirling boiler with my invention applied. Fig. 2 is an end view of the same, the left-hand half being a section on the line X-X of Fig. 1 with the fire-grate removed. Fig. 3 is a plan of the drums and connecting-tubes only, showing the baffles and the steam-pocket in dotted lines. 45

In the figures I have shown my invention applied to a Stirling boiler constructed with three upper steam and water drums a, b, and c,

connected to a single lower water-drum d by banks of tubes e, f, and g. The drums a, b, and c are connected together above the water-level by steam-tubes t and u and below the water-level by tubes s and q. The water-space of the drum c is divided into two spaces by the partition n, and the drum d is divided by a partition h into two spaces j and k, into 60 the latter of which the feed-water from the feed-pipe r in the drum c is passed by way of the tubes p. Communication between the spaces j and k is effected through holes m in the partition h. As, however, this boiler 65 forms the subject of a separate application, it is not necessary to further describe it in the present application.

In applying my invention according to one modification to a boiler of the above description I provide the central drum b with a box-baffle or pocket w, secured to the inside of the drum above the water-level. The main steam stop-valve x and a certain section of the steam-tubes u, (lettered z on Figs. 2 and 75 3,) communicate directly with this pocket w, which is shut off from the rest of the steam-space of the drum b. By means of this device the steam generated in the front drum a must pass through the pipes t into the central drum b 80 on its way to the stop-valve x. It cannot, however, pass direct to the stop-valve from this drum b, since the pocket closes off the steam-outlet; but it passes through the steam-pipes u, which are not included in the pocket, into 85 the feed-drum c, whence it passes by the tubes z into the pocket w and out through the stop-valve x to the engine in the manner indicated by the arrows in Fig. 3. The various changes in the direction of steam-flow caused 90 by this steam circulation produces a drying effect on the steam similar to that produced by steam-separators. This arrangement also increases the effective distance between the outlet x and the water-level practically to 95 that between the level of the water in the back drum c through the steam-pipes z and the outlet x.

I increase the effective distance between the water-level in the drums a and c and the connecting-pipes t, u, and z by means of inclined baffles or troughs 2, 2^a, and 3, respectively, secured to the inside of the drums a, b, and c opposite the mouths of the tubes

2
connecting the steam-spaces of the drums, the baffle 2 extending along the whole length of the drum *a*, the baffles 2^a occupying the spaces on each side of the box *w* opposite the tubes *u* in the drum *b*, and the baffles 3 opposite the mouths of the central section *z* of the tubes *u* in the drum *c*. The trough 2 extends the whole width of the tubes *t*, but the trough 3 obviously need only be the width of the section *z* of tubes *u*.

The troughs may be provided with a suitable drain-pipe or with holes to prevent the possibility of water lodging in them.

The whole boiler may be inclosed in a suitable casing, baffles being provided to direct the furnace-gases among the tubes in the most advantageous manner to an uptake 4, situated between two of the steam and water drums or in any other suitable position.

20 A boiler thus constructed is well adapted for marine purposes and other cases where space is valuable and lightness desired, while the production of dry steam under the most adverse circumstances is assured.

25 Having now described my invention, what I claim as new, and desire to secure by Letters Patent, is—

1. In a water-tube boiler constructed with

a plurality of steam and water drums the steam-spaces of which are in communication with each other, in combination, an internal pocket secured opposite the steam-outlet inside one of the steam-spaces, and tubes connecting the pocket with one of the other steam-spaces, whereby the steam from all the drums is caused to pass through these tubes into the pocket before passing through the steam-outlet, substantially as described.

2. In a water-tube boiler constructed with a plurality of steam and water drums the steam-spaces of which are in direct communication with each other, in combination, an internal pocket secured opposite the steam-outlet inside one of the steam-spaces, steam-tubes connecting the pocket with one of the other steam-spaces, and open-topped troughs secured to the inside of the drums opposite the mouths of the steam-tubes, substantially as described.

In witness whereof I have hereunto set my hand in presence of two witnesses.

JOHN COWAN.
